CLAIM

The ornamental design for a dual-cartridge dispenser for paste, as shown and described.

DESCRIPTION

FIG. 1 is a perspective view of a dual-cartridge dispenser for paste showing our new design;

FIG. 2 is a front view thereof;

FIG. 3 is a rear view thereof;

FIG. 4 is a left view thereof;

FIG. 5 is a right view thereof;

FIG. 6 is a top side view thereof;

FIG. 7 is a bottom view thereof;

FIG. 8 is another perspective view thereof; and,

FIG. 9 is an enlarged perspective view thereof showing a lower-middle part according to Circular Area circumscribed within FIG. 8.

In the drawings, the evenly spaced broken lines are for the purpose of illustrating environment only and form no part of the claimed design.

In the drawings, the line-dot-line broken line is for the purpose of circumscribing the Circular Area on FIG. 8 only and forms no part of the claimed design.
